(57) **CLAIM**

The ornamental design for a point of sale terminal, as shown and described.

DESCRIPTION

FIG. 1 is a perspective view of a point of sale terminal showing a first embodiment of the new design;

FIG. 2 is a front view of the point of sale terminal of FIG. 1;

FIG. 3 is a back view of the point of sale terminal of FIG. 1;

FIG. 4 is a right side view of the point of sale terminal of FIG. 1;

FIG. 5 is a left side view of the point of sale terminal of FIG. 1;

FIG. 6 is a top view of the point of sale terminal of FIG. 1;

FIG. 7 is a bottom view of the point of sale terminal of FIG. 1;

FIG. 8 is a perspective view of a point of sale terminal showing a second embodiment of the new design;

FIG. 9 is a front view of the point of sale terminal of FIG. 8;

FIG. 10 is a back view of the point of sale terminal of FIG. 8;

FIG. 11 is a right side view of the point of sale terminal of FIG. 8;

FIG. 12 is a left side view of the point of sale terminal of FIG. 8;

FIG. 13 is a top view of the point of sale terminal of FIG. 8; and,

FIG. 14 is a bottom view of the point of sale terminal of FIG. 8.

The broken lines depict environmental subject matter only and form no part of the claimed design.
